(57) **CLAIM**

The ornamental design for a tool, as shown and described.

DESCRIPTION

FIG. 1 is a perspective view of the front and a side of a tool showing a first embodiment of my new design;

FIG. 2 is a front elevational view thereof;

FIG. 3 is a rear elevational view thereof;

FIG. 4 is a side elevational view thereof;

FIG. 5 is a side elevational view thereof;

FIG. 6 is a bottom elevational view thereof;

FIG. 7 is a top elevational view of the thereof;

FIG. 8 is a perspective view of the front and a side of a tool showing a second embodiment of my new design;

FIG. 9 is a front elevational view thereof;

FIG. 10 is a rear elevational view thereof;

FIG. 11 is a side elevational view thereof;

FIG. 12 is a side elevational view thereof;

FIG. 13 is a bottom elevational view thereof; and,

FIG. 14 is a top elevational view of the thereof.

The broken lines in the drawings illustrate portions of a tool which form no part of the claimed design.

1 Claim, 6 Drawing Sheets(56)
